United States Patent Office.

JULIUS WILCKE, OF NEWARK, NEW JERSEY.

Letters Patent No. 77,694, dated May 5, 1868.

IMPROVEMENT IN PUMPS.

The Schedule referred to in these Letters Patent and making part of the same.

TO ALL WHOM IT MAY CONCERN:

Be it known that I, JULIUS WILCKE, of Newark, in the county of Essex, and State of New Jersey, have invented a new and useful Improvement in Pumps, of which the following is a full, clear, and exact description, reference being had to the accompanying drawing, forming part of this specification, and in which—

Figure 1 represents a longitudinal sectional view of a pump constructed according to my improvement, taken through the valve-cylinder or chamber thereof.

Figure 2, a transverse section of the same through the line $z z$ in fig. 1.

Figure 3, a longitudinal section of the self-acting valve-portion of the pump detached, and showing the valve in a reverse position to that represented for it in fig. 1.

Figure 4, longitudinal and end views of the self-acting valve detached; and

Figures 5 and 6 similar views or diagrams of modifications in the construction of said valve.

Similar letters of reference indicate corresponding parts.

This, my improved pump, which is applicable to raising, or raising and forcing, water or other fluids, and pumping air or gases, is of a double-acting character, and embraces a reciprocating piston working in a cylinder or barrel, communicating at its opposite ends with a valve-cylinder or chamber that contains an intermittently-reciprocating valve, preferably of tubular form, and provided with suitable ports or passages on opposite sides of a dividing-diaphragm or disk, and operating in a self-acting manner by the pressure of the fluid, in its delivery by the pump-piston, on the diaphragm, to control suction, and delivery-ways in or connected with the valve-cylinder or chamber.

The invention also consists in a peculiar split cylindrical construction of such self-acting valve, whereby, while it is free to operate as described, the pressure of the fluid serves to expand the same, and keep it tight, without the aid of packing.

Referring to figs. 1, 2, 3, and 4 of the drawing, A represents the pump-cylinder or barrel, carrying within it a reciprocating piston, driven, through a rod, B, by any suitable power. This cylinder A is connected, by passages, $a a'$, at or near either end, with a valve-cylinder or chamber, C, of cylindrical form, and provided with inlet-ports, $b b'$, communicating either with separate suction-pipes, or one, D, common to both, and also provided with a delivery-port, e, opening into or communicating with a discharge-pipe, E, that, or a suitable intermediate chamber, may be furnished with a check-valve, d.

Fitted to freely reciprocate within the cylinder A, is a tubular valve, F, open at its ends, which may be cut away, as at $s s$, so as, in the throw of the valve, not to cover the passages $a a'$, and which is constructed with a central or intermediate dividing-disk or diaphragm, e, and is furnished at its sides with ports or openings, $f f'$, communicating with or controlling the inlet-ports $b b'$, and other ports or openings, $g g'$, communicating alternately with the delivery-port e.

Now, it will be obvious that the reciprocating action of the pump-piston will serve to throw alternately to opposite ends of the cylinder C, the valve F, by the water previously sucked into the pump-barrel being forced by said piston through either one of the passages $a a'$, and caused to act upon one side of the diaphragm e, and the valve F, in thus being thrown by the pressure of the fluid, alternately in opposite directions, shutting off the port f or f' from communication with the inlet-port b or b' on the pressure or delivery side or end of the valve, and opening the other port f or f' on the suction side thereof, into communication with the other inlet-port b or b' to establish suction at the opposite end of the pump-barrel, through the port a or a' , for a reverse action of the piston; said valve also, in thus being thrown intermittently and automatically by the pressure of the fluid in or by the delivery from the pump-barrel, as the piston commences its return stroke, opening alternately the ports $g g'$ into communication with the delivery-port e, and the water thus discharged being prevented from returning by the check-valve d , though this latter valve may in some cases be dispensed with.

To prevent loss by leakage, and secure a tight yet free fit to the self-acting reciprocating valve F, without objectionable or expensive packing, I construct the tubular valve F with a number of slits or splits, h, running more or less in a longitudinal direction for any suitable distance or distances from the ends of the valve, so that the pressure of the fluid within the valve will act upon its split sides to expand or bear it against its cylinder. In this way

may a tight but easy fit be secured, and in a cheap and simple manner, the close character of the valve-cylinder and freedom from outside connections of the valve adding to its cheapness, simplicity, and exemption from leakage, while the whole arrangement constitutes a most efficient double-acting pump.

If preferred, the construction of the valve F and its chamber C may be modified by making them of square or other than cylindrical shape in their transverse sections, and having the suction and delivery-ports all arranged in or on the base or one side, as it were, the self-acting and diaphragm-divided valve not being split or slit, and bearing only on said side or base, as represented by the diagrams in figs. 5 and 6, where the valve is shown in red lines, said valve, on either side of its diagram, being constructed either with single ports, as shown in fig. 6, or with double ports, as shown in fig. 5, controlling the suction and delivery-ports of the valve-chamber.

What is here claimed, and desired to be secured by Letters Patent, is—

1. The combination, with the pump-barrel A, having within it a reciprocating piston and valve-cylinder or chamber C, connected with the pump-barrel by end-passages, *a a'*, of a loose or independent valve, F, constructed with an intermediate diaphragm, *e*, and separate suction and delivery-ports controlling separate suction and delivery-ports or passages in the valve-chamber, as the valve is shot by the pressure of the fluid at the commencement of the return stroke of the piston, substantially as specified.

2. The intermittently-reciprocating valve F, with its dividing-diaphragm, *e*, and side inlets and outlets, controlling suction and delivery-ports in the valve-cylinder by the pressure of the fluid in the discharge-stroke of the piston, as specified, when said valve is of tubular or cylindrical form, and made with splits or divisions H, to give to it an elastic character, essentially as shown and described.

JULIUS WILCKE.
